UNITED STATES PATENT OFFICE

ABRAHAM DEINSTEIN, OF CHICAGO, ILLINOIS

CIGARETTE

Application filed July 9, 1930. Serial No. 468,667.

In the manufacture of cigarettes it has been the practice to enclose a quantity of tobacco within a cylindrical casing or covering constructed of thin paper. In the ordinary type of cigarette both ends of the cylindrical wrapper or casing are left open so that any loose tobacco at the ends of the cigarette is permitted to fall or be discharged from the cigarette. It also often happens that when one end of a cigarette is inserted in a person's mouth that particles of the tobacco become dislodged from the end of the cigarette and fall into the person's mouth. Such a condition is exceedingly annoying and necessitates the removal of the cigarette from the person's mouth so that the loose tobacco which has been discharged therefrom may be expectorated. Another difficulty found with open ended cigarettes is that the tobacco at the ends of the cigarette wrappings or casings falls into the cigarette boxes or cases in which the cigarettes are being carried. This condition is not only annoying to the user of cigarettes but occasions a considerable waste of tobacco.

To obviate the loss of tobacco from the ends of cigarettes and to prevent the dropping of particles of tobacco from the supported end of a cigarette into a person's mouth this invention has been devised for the purpose of providing an improved type of cigarette having either one or both ends thereof closed by means of perforated caps or screen grid covers which serve to retain the tobacco within the cigarette wrapper or casing prior to the smoking of the cigarette and furthermore provide a screen cap which is adapted to be inserted in a person's mouth when the cigarette is to be smoked to afford a sanitary protecting means whereby loose tobacco is prevented from dropping into a person's mouth to cause annoyance and require expectoration of the loose tobacco. The perforated cap not only affords protection against the discharge of tobacco into a person's mouth but furthermore does not interfere with the proper draft being produced through the cigarette when it is smoked nor is the enjoyable taste and ease of smoking interfered with.

It is an object of this invention to provide a cigarette with a perforated cap or screen to obviate the loss of tobacco and afford a protection against nicotine and loose tobacco being discharged into a person's mouth when the cigarette is being smoked. 55

It is also an object of this invention to provide an improved simplified type of cigarette with an apertured closure cap on either one or both ends thereof. 60

It is an important object of this invention to provide an improved type of cigarette adapted to have an apertured cap or screen grid closure member engaged or formed on one or both of the ends thereof to conserve 65 and retain the tobacco within the cigarette casing and also act as a reinforced holding means for one end of the cigarette when the same is being smoked so that no tobacco is permitted to be discharged from the cigarette into a person's mouth. 70

Other and further important objects of this invention will be apparent from the disclosures in the specification and the accompanying drawings. 75

The invention (in a preferred form) is illustrated in the drawings and hereinafter more fully described.

On the drawings:

Figure 1 is a side elevation of an improved 80 cigarette embodying the principles of this invention.

Figure 2 is a fragmentary longitudinal enlarged section of the cap end of the cigarette.

Figure 3 is a perspective view of a modified 85 form of cigarette provided with an apertured closure cap at each end thereof.

Figure 4 is a fragmentary elevational view of a portion of a modified form of cigarette having a removable cap engaged on the end 90 thereof.

Figure 5 is a sectional view of the removable cap used in connection with the cigarette illustrated in Figure 4.

As shown on the drawings:

The reference numeral 1 indicates a tube, cylindrical casing or wrapper constructed of thin paper or the like usually used in the manufacture of the ordinary type of cigarette. The tubular casing or wrapper 1 is rolled 95

around a filling of tobacco 2 which is ordinarily compressed or packed during the rolling of the cigarette. Engaged on one end of the cigarette is a closure cap comprising an end disc or plate 3 provided with a peripheral flange or rim 4 which is engaged around the exterior of one end of the casing or wrapper 1 and is secured thereto by means of adhesive or by crimping as indicated at 5. The coating 10 of adhesive may be engaged around the exterior of one end of the cigarette casing 1 or if desired may be applied on the inner surface of the flange 4 forming part of the closure cap of the cigarette. The closure cap 15 consisting of the end plate 3 and the flange or rim 4 and is positioned to afford a mouthpiece or holder for closing one end of the cigarette to retain the tobacco therein thereby preventing the tobacco from becoming dislodged and falling into a person's mouth when the cap end of a cigarette is engaged in the person's mouth. The end plate 3 of the closure cap is provided with a plurality of apertures or openings 6 to permit a draft to 25 be created through the cigarette when the same is lighted and is being smoked. The closure cap is constructed of thin paper or other suitable material and serves to reinforce the closed end of the cigarette, so that the 30 apertured closure cap serves not only as a screen or grid preventing the discharge of tobacco into a person's mouth but also serves the purpose of providing a holder or reinforcing cap at one end of the cigarette and 35 prevents the capped end of the cigarette which is usually engaged in a person's mouth from shrinking or tearing which usually occurs in the ordinary type of cigarette because of the saturation of the paper covering at the 40 end of the cigarette which is engaged in the smoker's mouth.

Figure 3 illustrates a modified form of the device in which the reference numeral 7 indicates a cigarette having a flanged closure cap 45 8 engaged on each end of the cigarette. Each of the closure caps is provided with a plurality of apertures or openings 9 to permit a draft to be created through the cigarette when the opposite end of the cigarette is 50 lighted. The closure caps 8 are constructed of thin paper or other suitable material and may be secured in position by means of adhesive or the like. One capped end of the cigarette is adapted to be used as a holder for 55 insertion in a person's mouth and acts to prevent any of the tobacco in the cigarette from discharging or dropping into a person's mouth. The opposite capped end of the cigarette 7 is adapted to be lighted in the 60 usual way when the cigarette is to be smoked. The second cap is provided to close the second end of the cigarette so that before the cigarette is used and while it is in its package or in a holder the tobacco is prevented from 65 dropping out of either of the ends of the

cigarette. The closure caps not only prevents the waste of tobacco but serve to reinforce the ends of the cigarette and prevent the same from being crumpled or damaged before they are used.

Figures 4 and 5 illustrate another modified form of the device in which the reference numeral 10 designates a cigarette having a closure cap 70 removably or frictionally engaged on the end thereof. The closure cap 75 comprises an end plate 11 having draft or smoke openings 12 therein. Integrally formed on the closure plate 11 is a flange or rim 13 the rim or margin thereof being slightly deflected outwardly at 14 to afford an 80 enlargement at the open end of the cap so that the cap may be readily slipped or engaged upon one end of the cigarette 10. The closure cap may be so constructed that it will be frictionally retained in position and serve 85 both as a holder when the cigarette is being smoked as well as a reinforcing means for the end of the cigarette. The apertured closure plate 11 of the cap serves as a screen 90 grid or sieve for preventing the discharge of the tobacco from the end of the cigarette. If desired the type of cigarette illustrated in Figures 4 and 5 may have a closure cap engaged on one or both ends of the cigarette 95 similar to the arrangement illustrated in Figures 1 and 3 of the drawings.

In the modified form of cigarette illustrated in Figures 4 and 5 the apertured caps or closure members may be carried separately from the cigarette and may be engaged on 100 either one or both ends of the cigarette as desired so that the tobacco within the cigarette is prevented from falling out of the ends thereof. When a cigarette of this type is to be smoked the closure cap may be removed 105 from one end and the opposite or capped end may be used as a holder for engagement in a person's mouth so that the supported end of the cigarette is not only reinforced by the closure cap but has the tobacco separated 110 from contact with the interior of a person's mouth. The closure cap acts not only as a reinforcing means and a closure for the end of a cigarette but also provides the necessary draft openings so that the cigarette may be 115 conveniently smoked without any danger of tobacco falling into the person's mouth and without any impairment to the proper draft through the cigarette. The closure cap not only affords a reinforcement and a holder for 120 the cigarette but also permits the full enjoyment of the taste of the cigarette which is cherished by smokers.

Attention is also called to the fact that the improved apertured cap or holder engaged 125 on the end of the cigarette serves as a means for protecting the fingers of a person against danger of becoming stained by nicotine. The closure cap acts as a retaining means for holding the nicotine, resulting from the 130

smoking of the cigarette, within the cigarette casing at the closed end thereof, thereby preventing the nicotine from entering a person's mouth or from staining a person's fingers.

5 It will of course be understood that many details of construction may be varied through a wide range without departing from the principles of this invention, and it is therefore not the purpose to limit the patent granted hereon otherwise than necessitated by the scope of the appended claim.

10 I claim as my invention:

15 A cigarette comprising a casing having a filling of tobacco therein, closure means engaged on the ends of said casing to retain the tobacco therein, said closure means being constructed of substantially the same material as that of which the casing is constructed, one of said closure means serving as 20 a tip for the cigarette while the opposite closure means reinforces the end of the cigarette and serves as a mouth-piece preventing tobacco from dropping out of the end of the cigarette into the mouth of a person smoking 25 the same, said closure means having a plurality of spaced apertures communicating with the longitudinal axis of said casing.

20 In testimony whereof I have hereunto subscribed my name at Chicago, Cook County, Illinois.

ABRAHAM DEINSTEIN.
